UNITED STATES PATENT OFFICE.

JOHN G. H. LIEBEL AND EDWIN S. FLARSHEIM, OF CINCINNATI, OHIO.

TIME SWITCH.

Application filed November 26, 1921. Serial No. 518,049.

To all whom it may concern:

Be it known that we, JOHN G. H. LIEBEL and EDWIN S. FLARSHEIM, citizens of the United States, and residing at Cincinnati, in the county of Hamilton and State of Ohio, have invented a new and useful Improvement in Time Switches, of which the following specification is a full disclosure.

This invention relates to a portable time controlled electric switch of particular utility in X-ray photography, as an addition or improvement to the time switch disclosed in an application filed by us October 10, 1921, Serial No. 506,612.

15 The device provides for a manual circuit closing, for a current interrupting, and for time mechanism automatic control after a manual time setting is made. The time mechanism effects the automatic circuit opening or breaking, at the end of a measured duration, for which the time mechanism is initially set. The current control can be either continuous for the aggregate time of a given time setting, or intermittent 20 or interrupted for indefinite periods at the option of the operator. This provides for a single exposure of a definite time, or for a number of exposures, aggregating a definite time period established by a time setting. 25 The electric switch and clock mechanism of this invention is substantially the same as that of the invention disclosed in the before mentioned application, with the invention herein, dealing primarily with the mechanism for locking the push plunger of the electric switch against movement, in its normal position, to prevent accidental switch-closing, and to the means for making definite clock settings to eliminate dial reading 30 for a particular time setting or for repeated operations.

Therefore, it is an object of the invention to provide the actuating member of the portable electric switch with locking mechanism manually controlled for preventing accidental switch closing.

Another object of the invention is to provide a time limited electric switch with adjustable stop means for limiting a setting 40 adjustment of the time setting mechanism.

Other features and advantages of the invention will be more fully set forth in the description of the accompanying drawings,

forming a part of this specification, in which:

Fig. 1 is a central section illustrating the mechanism for throwing the switch, and for releasing the same at predetermined time intervals.

Fig. 2 is a section on line 2—2, Fig. 1, illustrating the plunger locking mechanism.

Fig. 3 is a section on line 3—3, Fig. 1, illustrating the method of plunger tripping.

Fig. 4 is a face view of the dial showing the adjustable stop means for limiting dial finger movement.

Fig. 5 is a section on line 5—5, Fig. 4.

Fig. 6 is a face view of the bar for locking the front plunger of the electric switch.

As the details of construction of the electric switch and its time controlling clock mechanism correspond substantially to the device made the subject-matter of the aforesaid application, reference should be had to said application for a detailed description 85 of such parts or mechanism, which are herein referred to in a general manner sufficient for the present purpose.

Referring to the drawings, 1 indicates a cylindrical casing preferably of an electric insulating material within which the electric switch mechanism is mounted. The casing is of such dimensions as to be held in the hand of the operator and the electric switch is housed within the casing operated by a push-plunger 2 projecting through one end of the casing to be engaged by the thumb of the operator. The plunger 2 is depressed for an electric switch or circuit closing operation and is slidable within a sleeve 3 within the casing and fixed to the head of the casing. This sleeve supports and guides the push-plunger centrally over the electric switch elements consisting of yielding contact blades 4, 5, for making and breaking or controlling an electric circuit. The plunger may be said to be of two-part form, the parts unitarily movable for closing the electric switch or bringing the contact blades 4, 5, into engagement, with one part releasably connected with the second and adapted to be tripped by the clock mechanism for an automatic release of the contact blades for breaking the electric circuit at the end of the time period.

Thus the plunger 2 is provided with a plug extension 6 slidably en-

gaged within a tubular end thereof, and adapted to engage the switch blade 4 when the plunger is depressed. The plug as an extensible plunger end is coupled to the 5 plunger by an arm 7 extending radially from the plug and through an L-slot in the plunger, the L-slot providing a shoulder 8 at one end of the slot against which the arm engages for unitarily connecting the parts 10 for a switch control. The arm, when the plunger is depressed, may be tripped from the shoulder for releasing the plug, the plug when so released being retractably moved independently of the plunger under the 15 spring pressure of the switch blade 4 for a time-controlled automatic circuit breaking operation. The trip arm 7 is provided with an angle-knife extension 9 cooperating with a lever arm 10, fixed upon the end of the 20 clock shaft 11. When the plunger and movable plug end are depressed, the knife end of the arm 7 is disposed in the path of the lever or crank arm 10 and when engaged thereby rotates the plug slightly and to a 25 degree which will disengage the arm 7 from the shoulder 8, whereupon the plug is free to be retracted within the plunger under the releasing pressure of the spring switch blades, whereby the contacting engagement 30 between the switch blades is broken, opening the circuit controlled thereby while the plunger remains depressed.

This provides for an automatic breaking of the electric circuit after a definitely timed 35 period beyond the manual control of the operator, by maintaining the plunger in depressed position. The circuit, however, can be broken at the will of the operator within a timing period and before the trip arm is 40 engaged by the clock arm 10, by merely releasing the plunger, as the plunger and its extensible plug end move as a unit as long as the arm 7 is permitted to remain engaged with the shoulder at the end of the L-slot 45 in the plunger. When tripped, the plunger must be fully retracted before the plunger parts are re-engaged. When the plunger and its extensible plug end are depressed, the knife end of the trip arm 7 cooperates with 50 an escapement controlling lever 12, of the clock mechanism, for releasing the clock mechanism, and its operation checked immediately upon the disengagement of the trip arm 7 and escapement controlling lever 55 12. The clock mechanism only continues in operation while the plug end of the plunger remains depressed.

This provides for either a continuous or 60 intermittent electric circuit control for a given or predetermined time setting. The plunger is retracted by a spring 13 interposed between the plunger head and the end of the sleeve 3.

To avoid accidental depression of the 65 plunger, spring lock mechanism is employed,

consisting of a lock lever 14 loosely engaged upon a pin 15 extended from the sleeve 3. The pin 14^a projecting from the forward end of the lock lever 14 engages through an aperture 16, in the sleeve 3, and into a notch 70 or aperture 17, in the plunger 2, when the plunger is in its normal retracted position. A pin extension 18, on the rear side of the lock lever, provides a stop for a limited releasing motion of the lever. The lever is 75 spring pressed by a leaf spring 19, fixed upon the rear end of the lock lever and engaging or bearing against the interior of the casing 1. The lock lever is actuated by a push-button 20 engaged through an orifice 80 in the casing and protrudes slightly beyond the exterior of the casing, so as to enable the button to be depressed when the casing is grasped by the palm of the operator's hand. By depressing the push-button 20, the lock 85 lever is rocked for releasing the plunger 2.

The clock mechanism, under the arrangement shown, has its time-setting mechanism limited to a single cycle of the setting pointer 21 fixed upon the outer end of the 90 clock shaft 11, the pointer at the end of a cycle being stopped by a pin 22 projecting from the face of the dial plate 23. The end of the clock shaft 11 is provided with a thumb nut 24, by which the shaft 11 is manually rotated for a clock setting and winding operation. The clock mechanism is housed within a cylindrical casing extending at right angles from the main casing 1. The outer end of the clock casing has a 100 flanged annulus 25 for securing a transparent cover disc 26 in place, as a closure for the end of the clock casing. The pointer 21 is disposed between the clock dial plate 23 and the transparent cover disk 26, with the dial plate and cover disk spaced apart by a ring bushing 27, the outer edge of the ring bushing providing an annular shoulder against which the cover disk bears, while the casing annulus is flanged to engage the opposite or outer side of the cover disk. The cover disk is rotatable within the seat space by the bushing and casing annulus, and is provided with an aperture 28 through which a stop pin 29 engages for intercepting the 110 pointer 23. The stop pin is fixed or integral with the end of a bar 30, fixed to an annulus 31, rotatable about the casing annulus over which it is engaged and to which it is 115 adapted to be clamped by a clamp consisting of a jaw member 32, engaging the inner edge of the casing annulus and provided with a screw stem 33, engaged through the annulus 31, its free end carrying a thumb nut 34, adapted to bear against the outer 120 face of the annulus 31. The clamp frictionally clamps the annulus 31 to the casing annulus 25 in any rotative adjusted position. Thus the stop pin 29 can be adjusted 125 and set about the dial face as a time pre- 130

setting limit to which the pointer can be set. As shown, the stop pin is set between the dial readings 2-3, furnishing at such point a pre-set limit to which the pointer or clock-setting indicator hand can be rotated.

For changing the setting limit, the clamp is released, which permits the limit setting annulus to be freely swivelled or rotated, to bring the stop pin to any time setting limit desired within a single cycle of the clock setting indicator or pointer, whereupon the annulus is again rigidly clamped against rotation.

15 This is of material advantage to the operator in X-ray photography for making a quick and accurate time setting and for repeated operations, without being required to observe the dial graduations for an indicator setting.

Having described our invention, we claim:

1. In a device of the class described, a casing, an electric circuit controlling switch mounted within said casing, a depressible 25 push-plunger slidable within the casing for manually operating said switch and extending through one end of the casing, said plunger being of two-part form, with the parts operable unitarily and independently 30 of one another, rewind setting clock mechanism for timing a closed duration control of said switch, cooperating with one part of said plunger, and push-button actuated locking means adapted to cooperate with said 35 plunger for locking said plunger in its normal position.

2. A portable hand-holding time limited electric circuit controlling device, comprising a cylindrical casing, an electric circuit 40 controlling switch mounted within said casing, a push-plunger slidable within the casing for actuating said switch and extending through one end of the casing, push-button actuated locking means accessible from the 45 exterior of the casing, for locking said push-plunger in its normal position, and clock mechanism for controlling a switch closing duration cooperating with said push-plunger.

50 3. In a device of the class described, a cylindrical casing, a rewind time-setting clock mechanism, having an indicating finger mounted within said casing, an annulus swivelled upon the face end of said casing, clamping means for clamping said annulus to said casing, and a finger stop element

mounted on said annulus, projecting in the path of said finger to intercept the same and provide an adjustable clock time-setting limit.

4. In a device of the class described, a casing, a rewind time-setting clock mechanism mounted within said casing and having a setting indicator finger, a dial for said finger, stop means for said finger swivelled about the axis of said finger, and means for clamping said stop means against motion.

5. In a device of the class described, a casing, a rewind time-setting clock mechanism mounted within said casing, having a manually operable rewind and setting shaft, accessible from the exterior of the casing, an indicator dial disk axially with said shaft, an indicator finger mounted on said shaft, a transparent plate about said shaft, providing an end closure for said casing, and housing said finger, an annulus about the axis of said shaft, exterior of said transparent plate, having a finger stop element engaged through an aperture in said plate for finger interception, and friction clamping means for rigidly clamping said annulus to the casing.

6. In a device of the class described, a casing, having an annular rim end, a time indicator dial mounted within the rim end of said casing, clock mechanism within said casing having a clock winding and setting shaft extended through said dial, an indicator finger fixed to said shaft, a ring swivelled upon said casing ring, carrying a stop member for intercepting said indicator finger, and clamping means for locking said ring to said casing rim.

7. In a device of the class described, a casing, having an annular rim bound dial opening, a clock mechanism within said casing having a clock winding and time setting shaft coaxial with said casing rim, and carrying an indicator finger, an annulus swivelled about said rim, carrying a stop member for intercepting said finger, and means for clamping said annulus against motion.

In witness whereof, we hereunto subscribe our names, as attested by the two subscribing witnesses.
